RADIO RECEIVER

Wendell L. Carlson, Haddonfield, N. J., assignor
to Radio Corporation of America, a corporation
of Delaware

Application September 27, 1933, Serial No. 691,120

16 Claims. (Cl. 250—20)

My invention relates to radio receivers and particularly to a receiver designed to be operated either as a conventional highly selective receiver or as a high fidelity receiver designed to suppress part of one side band of the incoming signal.

The usual broadcast transmitter transmits a signal which consists of a carrier wave and the upper and lower side bands. The conventional receiver is tuned to the carrier wave frequency so that equal amounts of the two side bands are received. With a crowded broadcast band such a receiver generally must be so sharply tuned that the high frequency components of the side bands are cut off, whereby the quality of the reproduced voice or music from a received modulated carrier wave is impaired.

The cutting off of the side bands may be avoided by merely broadening the tuning of the receiver circuits, but this is objectionable for two reasons. In the first place, it greatly lowers the gain of the receiver, and in the second place, it permits interference from stations on adjacent channels.

It is, accordingly, an object of my invention to provide an improved receiver which may be operated selectively either as a conventional receiver or as a high fidelity receiver.

It is a further object of my invention to provide a high fidelity receiver that shall have comparatively high gain and improved selectivity.

It is a still further object of my invention to provide an improved receiver for receiving mainly the carrier and one side band of a radio signal wave.

In practicing my invention, and in a preferred embodiment thereof, I provide a superheterodyne receiver with a control circuit which is sharply tuned to the intermediate frequency for the purpose of making the receiver inoperative until it is tuned exactly to the carrier frequency of the desired station. Operated in this manner, the receiver is sharply selective. I further provide switching means for broadening the tuning of certain circuits on one side of the carrier frequency only, whereby the receiver may be operated as a less sharply selective, high fidelity receiver. The tuning is broadened sufficiently to permit the passage of one complete side band. The other side band, except the lower frequency end thereof, is appreciably attenuated or suppressed.

It is evident that the receiver, when operating as a single side band, high fidelity receiver must always be tuned to a single side band of an incoming signal before the above-mentioned con-

trol circuit permits the receiver to operate. In other words, the receiver must be tuned to one side of the middle of the main channel.

Other features and advantages of my invention will appear from the following description taken in connection with the accompanying drawings, in which

Figure 1 is a circuit diagram of a receiver constructed in accordance with one embodiment of my invention;

Figs. 2 and 3 are curves showing the selectivity characteristics of certain tuned circuits of the receiver shown in Fig. 1; and

Fig. 4 shows certain signal output characteristics of the receiver shown in Fig. 1.

Referring to the embodiment of my invention shown in Fig. 1, it comprises a superheterodyne receiver which includes a radio frequency amplifier tube 1, a first detector tube 3, an intermediate frequency amplifier tube 5, and a second detector tube 7. These amplifier and detector tubes may be any suitable type of space discharge device. In the example illustrated, they are conventional screen grid and three element tubes.

The amplifier tube 1 is provided with an input circuit which includes a radio frequency transformer 9 having a primary winding 11 and a secondary winding 13, the primary winding 11 being connected to an antenna 15 and to ground.

In order to make the winding 13 tunable at radio frequencies, it is shunted by a variable tuning condenser 17, a blocking condenser 19, and a fixed tuning condenser 21, all connected in series. This tunable circuit will be referred to as the selecting or filter circuit A. The fixed tuning condenser 21 is provided with a short circuiting switch 23 for changing the tuning of the selecting circuit A when the receiver is to be adjusted for single side band reception. The control grid of the amplifier tube 1 is provided with a constant negative bias by means of a grid biasing resistor 25 connected in the cathode lead and shunted by a radio frequency bypass condenser 27. It is also provided with a variable biasing or controlling potential as hereinafter described.

The amplifier tube 1 is provided with an output circuit which is coupled to the input circuit of the detector tube 3 through a transformer 29. The secondary 31 of the transformer 29 is shunted by a variable tuning condenser 33 and a blocking condenser 35 connected in series to form a second radio frequency filter circuit A'. The condensers 17 and 33 are units of a gang condenser which

are operated by a common control as indicated by the dotted line 37.

When the receiver is operated as a conventional, sharply selective receiver, the condenser 21 is short-circuited and the tuned circuits A and A' are tuned to the same frequency. When operated as a high fidelity receiver, the switch 23 is open and the circuit A is tuned to a slightly higher frequency than the circuit A'.

10 The superheterodyne oscillator 39, which is coupled as indicated, to the first detector 3 for producing the intermediate frequency signal, may be of any suitable type. It includes a tuning condenser 41 which is operated as indicated, by 15 the above-mentioned common control for setting the oscillator at a frequency above that to which the radio frequency circuits are tuned by an amount equal to the intermediate frequency.

The detector tube 3 is provided with an output 20 circuit which is coupled to the input circuit of the intermediate frequency amplifier tube 5 through a transformer 43.

The primary winding 45 and the secondary winding 47 of the transformer 43 are tuned by 25 means of condensers 49 and 51, respectively, to form a band pass filter B of the type commonly employed in superheterodyne receivers. The tuning condenser 49 is connected in series with a second tuning condenser 53 which is provided with 30 a short circuiting switch 55. When the switch 55 is closed, the band pass range of the filter B is made wider and shifted to a slightly lower frequency.

The control grid 56 and the cathode 58 of the 35 intermediate frequency amplifier tube 5 are connected to the tuned secondary circuit of the filter B. The connection of the cathode 58 to this circuit is made through automatic volume control circuits which will be described hereinafter.

40 The control grids of both the first detector tube 3 and the intermediate frequency tube 5 are supplied with the proper constant bias by means of resistors 57 and 59 in the cathode leads, these resistors being shunted by radio frequency bypass condensers 61 and 63, respectively.

The output of the amplifier tube 5 is fed to the input circuit of the second detector tube 7 through a radio frequency transformer 65 having a primary winding 67 and a secondary winding 69. Tuning condensers 71 and 73 are connected across the windings 67 and 69, respectively, to form a band pass filter C having a predetermined selectivity characteristic.

In order to broaden the tuning of the filter 55 C for high fidelity reception, a coupling coil 75 is connected in series with the secondary winding 69 and coupled as indicated, to the primary winding 67. A switch 77 is provided for connecting the tuning condenser 73 across or in parallel with 60 either the secondary winding 69 itself, or the secondary winding 69 and the winding 75 in series. By throwing the switch 77 to the position shown to connect condenser 73 across both windings, the tuning of the filter C is broadened to 65 avoid the cutting off of the carrier wave side bands. This broadening of the tuning is caused by the increase in coupling between the primary and secondary circuits, as explained in my Patent No. 1,871,405. The amount of inductance 70 in coil 75 and the degree of coupling to primary 67 are adjusted so as to obtain the desired frequency range with the same increase of frequency range on each side of resonance compared to the sharp resonant circuit.

75 The audio frequency output of the second de-

tector 7 is supplied to a suitable audio frequency amplifier or translating device (not shown) through an audio frequency transformer 79.

The above described superheterodyne receiver is provided with an automatic volume control or 5 A. V. C. circuit which includes an intermediate frequency amplifier tube 81 and a rectifier tube 83.

In the particular embodiment shown, the amplifier tube 81 is of the screen grid type having a 10 control grid which is maintained at the desired negative potential through a biasing resistor 85 in the cathode lead.

The input circuit of the amplifier 81 is coupled to the output circuit of the band pass filter B 15 by means of a coupling condenser 87 and grid impedance 88.

The amplifier tube 81 is provided with an output circuit which is coupled to the input circuit of the rectifier tube 83 through a three winding transformer 89. The primary winding 91 of the transformer 89 is tuned to the intermediate frequency by means of a condenser 93. The secondary winding 95 is in the rectifier circuit and is closely coupled to the primary winding 91 25 to broaden the frequency range of the transformer.

The input circuit of the rectifier tube 83 includes a resistor 97 and a source of biasing potential such as a biasing battery 99, connected in 30 series with the secondary winding 95 and the resistor 97. When intermediate frequency signal energy is fed to rectifier 83, a voltage drop having a value depending upon the strength of an incoming signal will appear across resistor 97. The 35 voltage drop across the entire resistor 97 is applied to the control grids of amplifier tube 1 and detector tube 3 through a conductor 101 and filter resistors 103 and 105. A filter condenser 107 connected between the end of the resistor 97 40 and ground prevents audio frequency signals from appearing in the output of the volume control circuit in accordance with well known practice.

The voltage drop across a portion of the resistor 45 97 is applied to the control grid 56 of the intermediate frequency amplifier tube 5 through a conductor 109. This portion of the resistor is shunted by another filter condenser 111.

The biasing battery 99 prevents the A. V. C. 50 circuit from becoming effective to reduce the gain of the receiver until after the strength of the incoming signal exceeds a predetermined value, since the anode of rectifier 83 is maintained negative until the signal voltage across the secondary 55 95 exceeds said value.

In accordance with my invention, the receiver is also provided with a highly selective circuit 60 tuned to the intermediate frequency for maintaining the receiver in an inoperative condition except at the times that the said highly selective circuit is passing energy. This circuit, which may be referred to as the quiet automatic volume control or Q. A. V. C. circuit, includes an intermediate frequency amplifier tube 113, a rectifier tube 115 and a control tube 117.

The intermediate frequency amplifier tube 113, which is of the screen grid type in the example illustrated, has its input electrodes coupled to the output circuit of the preceding amplifier tube 81 70 by means of the other secondary winding 119 of the intermediate frequency transformer 89, the secondary winding 119 being loosely coupled and sharply tuned to the intermediate frequency by means of a condenser 121. The intermediate 75

frequency amplifier 113 is provided with an output circuit coupled to the input circuit of the rectifier tube 115 through an intermediate frequency transformer 123. The transformer 123 is sharply tuned to the intermediate frequency by means of condensers 125 and 127.

The control tube 117 is of the three-electrode type having a cathode 129, a control grid 131, and an anode 133. The cathode 129 is connected through a conductor 135 to the cathode end of the biasing resistor 59 of the intermediate frequency amplifier 5.

The anode 133 is supplied with positive potential from any suitable source such as a battery 137 connected between the anode 133 and ground. It will be seen that so long as current flows through the control tube 117, there is flow of current through the biasing resistor 59 of amplifier tube 5 in such a direction as to increase the negative bias of the control grid 56. The Q. A. V. C. circuit is so adjusted that normally this flow of current is sufficient to make the control grid 56 so negative that the amplifier tube 5 is made ineffective and the receiver is substantially inoperative to receive signals.

The control grid 131 of the control tube 117 is connected to the input circuit of the rectifier tube 115 at a point between the secondary winding 139 of the transformer 123 and a resistor 141 connected in series therewith and shunted by a filter condenser 145. The cathode 129 of the control tube 117 is connected to the cathode 143 of the rectifier tube 115 whereby any potential drop appearing across the resistor 141 is applied to the grid 131 of the control tube 117.

So long as no signal reaches the rectifier tube 115, the grid of the control tube 117 is in the same potential as its cathode 129, and the current flow through the control tube 117 maintains the intermediate frequency amplifier 5 in an inoperative condition. As soon as intermediate frequency energy is impressed upon the rectifier 115, however, the grid of the control tube 117 is made negative with respect to its cathode 129, due to rectified current flowing in resistor 141, whereby the current flow through the control tube is either decreased or stopped entirely, thereby reducing or removing the high negative potential from the control grid 59 of the intermediate frequency amplifier 5 and rendering the receiver operative to receive signals.

The specific A. V. C. and Q. A. V. C. circuits described in this application are disclosed and claimed in application Serial No. 648,422, filed December 22, 1932, as the joint invention of W. L. Carlson and L. R. Kirkwood, and assigned to the Radio Corporation of America.

The operation of the receiver will be more clearly understood by referring to the curves shown in Figs. 2 and 3. In Fig. 2, the curves show the selectivity of the radio frequency circuits A and A' for the conditions both of high selectivity and high fidelity.

For the condition of high selectivity, the switch 23 is closed and the circuits A and A' are tuned to the same signal frequency, the selectivity of the two circuits combined being shown by the dotted line curve 147. For this condition of operation, the switch 55 of filter B is open and switch 71 of filter C is in its upper position to give filters B and C a selectivity characteristic shown by the dotted line curve 149 in Fig. 3.

The selectivity of the Q. A. V. C. circuit is shown by the curve 151 in Fig. 3. It will be noted that for the condition of high receiver selectivity,

the Q. A. V. C. circuit is tuned to the middle of the "pass" range of the filters B and C.

With the switches thrown to the positions shown in Fig. 1 for high fidelity reception, the resonance curve of circuit A is shifted to a higher frequency as shown by the curve 153 in Fig. 2, the resonance curve 155 of circuit A' remaining unchanged. The combined selectivity of circuits A and A' is represented by the curve 157.

Also, as shown by the curve 159 in Fig. 3, the "pass" range of filter B is widened and shifted to a lower frequency range which includes all the lower side band of the intermediate frequency signal. The "pass" range of filter C is increased on both sides of the intermediate frequency, that is the tuning of the filter is merely broadened as indicated by the curve 161.

An inspection of Figs. 2 and 3 shows that at the normal or highly selective setting of the receiver, the high frequency components of the side bands are cut off both by the circuits A and A' and by the band pass filters B and C. It will be seen, however, that at the high fidelity setting of the receiver, that is, with the switches 23, 55, and 71 in the positions shown in Fig. 1, the entire upper side band of the radio frequency carrier is transmitted together with the lower frequency end of the lower side band. It will be noted that the upper side band of the radio frequency carrier wave corresponds to the lower side band of the intermediate frequency carrier wave, as indicated in Fig. 3. This side band inversion follows from the fact that the superheterodyne oscillator frequency is higher than the signal frequency.

For the condition of high fidelity reception, the Q. A. V. C. circuit is tuned to a frequency within but at one end of the "pass" range of the filter B as will be apparent by comparing curves 151 and 159 in Fig. 3. This new relation between the filter circuits, it will be understood, is caused merely by operating a switch control to shift the tuning of the circuits A, B, and C. Because of this relation, the receiver, when set for high fidelity reception, must always be tuned to one side band of a carrier wave before a signal appears in the receiver output circuit.

The curves in Fig. 4 show the audio frequency gain of the receiver plotted against frequency for the two conditions of operation. The curve indicated at 163 is for the condition of high selectivity, while the curve indicated at 165 is for the condition of high fidelity reception.

The most important difference between the two curves is that the gain for high fidelity reception holds up at the high frequency end after the gain for normal reception has dropped to a low value. It will be noted that the curve 165 shows the gain to be higher for low frequency signals than for the high frequency signals. This difference in gain is caused by the fact that the low frequency signal components of both side bands are passed by the filter circuits.

Although the receiver has been described as adjusted for reception of the upper side band of the radio frequency carrier wave, it could equally well be adjusted for reception of the lower side band only. Furthermore, various other switching arrangements for controlling the selector circuits may be provided. For example, the tuning of circuit A' may be shifted in place of the tuning of circuit A; the tuning of the secondary circuit of filter B instead of the primary circuit may be changed; and the band pass characteristic of filter C may be shifted the same as for

filter B although the circuit illustrated is advantageous since the gain is not changed when the tuning is changed.

It will be apparent that, instead of changing the capacity in circuits A and B, the inductance may be changed by proper switching. In the case of circuit A, however, the capacity change is preferred since it broadens the tuning the most at the lower carrier frequencies. At the higher frequencies, as at the upper end of the broadcast band, the tuning is normally rather broad and need not be broadened appreciably by the switching.

My invention is of particular importance where the signals to be amplified have such a high frequency that it is difficult to obtain the desired amplification. In television reception, for example, with the circuits tuned broadly enough to receive both side bands with high fidelity, the maximum gain per stage is about 4. By employing my invention for high fidelity reception, the gain per stage may be made about 6.

My invention provides improved selectivity since on one side of the received carrier there will be a wide spacing between the cut-off frequency of a filter and the adjacent transmission channel. This improvement in selectivity will be apparent by comparing curves 159 and 161 in Fig. 3 since, if the tuning of the circuits were merely broadened for high fidelity reception, the selectivity curve for the receiver would be similar to the curve 161 for filter C.

A further advantage of my invention resides in the simplicity of the switching arrangement, only three switches being required in the receiver shown in Fig. 1. If the tuning were broadened for receiving both side bands, it would be necessary to employ more switches.

Various other modifications may be made in my invention without departing from the spirit and scope thereof, and I desire, therefore, that only such limitations shall be placed thereon as are necessitated by the prior art and set forth in the appended claims.

45 I claim as my invention:

1. In a superheterodyne receiver, a first detector and a tunable oscillator coupled thereto for converting an incoming radio frequency signal to an intermediate frequency signal having at least one side band, a second detector, a band-pass filter for passing signals within a band of frequencies approximately the width of said side band, said band-pass filter being connected between said two detectors, and means including a sharply resonant filter tuned to a frequency near one end of said band of frequencies for controlling the operativeness of said receiver.

2. In a superheterodyne receiver, a first detector and a tunable oscillator coupled thereto for converting an incoming radio frequency signal to an intermediate frequency signal having at least one side band, a second detector, a band-pass filter for passing a band of frequencies approximately the width of said side band, said band-pass filter being connected between said two detectors, a sharply resonant filter coupled to said receiver at a point between said two detectors, said sharply resonant filter being tuned to a frequency near one end of said band of frequencies, means for making said receiver normally inoperative, and means for making said receiver operative in response to the passage of energy through said sharply resonant filter.

3. In a superheterodyne receiver, a first detector and a tunable oscillator coupled thereto

for converting an incoming radio frequency signal to an intermediate frequency signal having at least one side band, a second detector, a band-pass filter for passing a band of frequencies approximately the width of said side band, said band-pass filter being connected between said two detectors, a sharply resonant filter coupled to said receiver at a point between said two detectors, said sharply resonant filter being tuned to said intermediate frequency, means for making said receiver normally inoperative, and means for making said receiver operative in response to the passage of energy through said sharply resonant filter.

4. In a radio receiver, means for selecting a high frequency modulated carrier wave including a plurality of tunable signal selecting circuits at least one of which is adjustable to respond to one side band of the modulated carrier wave, an intermediate frequency amplifier comprising a plurality of tuned signal selecting circuits at least one of which is adjustable to respond to the intermediate frequency carrier wave and side band corresponding to said selected high frequency carrier wave and side band, an automatic volume control signal rectifier device coupled to said intermediate frequency amplifier to receive the intermediate frequency carrier wave, and means for rendering said receiver operative to receive signals including a signal rectifier device and intermediate frequency coupling means therefor comprising at least one tuned coupling circuit sharply responsive to the intermediate frequency carrier wave alone.

5. In a radio receiver, means for selecting an incoming signal comprising a modulated carrier having at least one side band, means for converting said incoming signal to a signal comprising a predetermined intermediate frequency carrier having at least one side band, an intermediate frequency amplifier which includes a tuned coupling circuit, said tuned circuit being adjustable to select only said one intermediate frequency side band, and means for making said receiver operative only in response to so adjusting said converting means that said one side band falls within the "pass" range of said tuned circuit, an automatic volume control system having a tuned signal input circuit responsive to a frequency within the "pass" range of said tuned circuit, and a quiet automatic volume control system having a tuned signal input circuit more sharply responsive than said automatic volume control system to a frequency also within the "pass" range of said tuned circuit.

6. In a superheterodyne receiver, a first detector tube and a tunable oscillator coupled thereto for converting a modulated incoming radio frequency signal to an intermediate frequency signal having at least one side band, a second detector tube, a plurality of amplifier tubes, all of said tubes being connected in cascade, a band-pass filter for passing a band of frequencies approximately the width of said side band, said intermediate frequency being at one end of said band, said band-pass filter being connected between said two detectors, and means including a sharply resonant filter tuned to said intermediate frequency for increasing the gain of at least one of said tubes in response to passage of energy through said sharply resonant filter.

7. In a radio receiver, means for selecting an incoming signal comprising a modulated carrier having at least one side band, means for selecting said one side band of the incoming signal, means

for converting said incoming signal and side band to a signal comprising a predetermined intermediate frequency carrier having a corresponding side band, a filter for selecting said one intermediate frequency side band and carrier, and means for making said receiver operative only in response to so adjusting said converting means that said one side band falls within the "pass" range of said filter.

10. 8. In a superheterodyne receiver, means for selecting an incoming radio-frequency signal including a carrier and at least one side band, means for converting said signal to an intermediate frequency signal including at least one side band, a filter for selecting said one side band, and means including a sharply resonant filter for making said receiver operative only when energy at said intermediate frequency is impressed upon said resonant filter, said sharply resonant filter being tuned to a frequency lying within and at one end of the frequency range of said first filter.

9. In a radio receiver, means for converting an incoming signal consisting of a modulated carrier wave having side bands to a signal consisting of a carrier wave having a predetermined intermediate frequency and having side bands, means for selecting one of said intermediate frequency side bands, said selecting means including a band-pass filter having a "pass" range approximately the width of said one side band, a sharply tuned filter tuned to a frequency within and at one end of said "pass" range, means for impressing at least a portion of said converted signal upon said sharply tuned filter, and means for making said receiver operative only when said sharply tuned filter passes energy.

10. In a superheterodyne receiver, a first detector tube and a tunable oscillator coupled thereto for converting a modulated incoming radio frequency signal to an intermediate frequency signal having two side bands, a second detector tube, a filter connected between said detector tubes and tuned broadly to said intermediate frequency whereby a portion of said side bands are transmitted, means including a sharply resonant filter tuned to said intermediate frequency for increasing the response of said receiver in response to the passage of energy through said sharply resonant filter, and means for so changing the tuning of said first filter that it may transmit substantially all of one of said side bands and only a small portion of the other of said side bands.

11. In a superheterodyne receiver, a first detector tube and a tunable oscillator coupled thereto for converting incoming radio frequency signals to intermediate frequency signals, a second detector tube, a filter connected between said detector tubes for passing a band of frequencies, said intermediate frequency being in the middle of said band, means including a sharply reso-

nant filter tuned to said intermediate frequency for increasing the response of said receiver in response to the passage of energy through said sharply resonant filter, and means for broadening the tuning of said first filter on one side only of said intermediate frequency when desired. 5

12. A radio receiver comprising means for selecting a signal having a carrier frequency and at least one side band, a filter for selecting said one side band only, and means including a sharply resonant filter for making said receiver operative only when said one side band falls within the "pass" range of said first filter. 10

13. A radio receiver comprising means for selecting a signal having a carrier frequency and at least one side band, a filter for selecting said one side band only, and means including a sharply resonant filter for making said receiver operative only when said sharply resonant filter passes energy, said sharply resonant filter being tuned 20 to a frequency lying within and at one end of the frequency range of said first filter.

14. In a radio receiver of the superheterodyne type, a tunable radio frequency circuit for selecting an incoming signal, an intermediate frequency selecting circuit, and means for simultaneously shifting the tuning of said radio frequency circuit to select one side band only of a desired signal and the tuning of said intermediate frequency circuit to select the corresponding 30 intermediate frequency side band. 25

15. In a radio receiver, means for selecting an incoming signal comprising a modulated carrier having at least one side band, means for converting said incoming signal to a signal comprising a predetermined intermediate frequency carrier having at least one side band, an intermediate frequency amplifier which includes a tuned coupling circuit, said tuned circuit being adjustable to select only said one intermediate frequency side band, and means for making said receiver operative only in response to so adjusting said converting means that said one side band falls within the "pass" range of said tuned circuit. 35 40 45

16. In a wireless or like receiver for modulated carrier-wave transmission, signal-selective means comprising the combination of a resonant device of low damping tuned to the frequency of the carrier wave of the signal, a comparatively broadly-tuned resonant device for receiving at least one side-band of the signals at substantially uniform amplitude, means for applying the signals to both of said resonant devices, means for controlling the total output of the receiver according to the strength of the signals, and means controlled by the output of at least one of said resonant devices for suppressing the total output of the receiver when minimum signals are received. 50 55 60

WENDELL L. CARLSON.
